(57) **CLAIM**

We claim the ornamental design for a voice over internet protocol (VoIP) phone, substantially as shown and described.

DESCRIPTION

FIG. 1 is a front view of the VoIP phone;

FIG. 2 is a back view of the VoIP phone showing an embodiment consisting of FIGS. 1, 2, & 4 collectively.

FIG. 3 is a back view of the VoIP phone showing a second embodiment consisting of FIGS. 1, 3, & 4 collectively; and, FIG. 4 is a side view of the VoIP phone.

The broken lines are superimposed on a continuous surface and are for illustrative purposes only; the broken lines form no part of the embodiment in which they are shown.
